UNITED STATES PATENT OFFICE.

JOSEPH IRWIN POGUE, OF OMAK, WASHINGTON.

BOX-PRESS STAMP.

Application filed August 11, 1921. Serial No. 491,409.

To all whom it may concern:

Be it known that I, JOSEPH IRWIN POGUE, a citizen of the United States, and resident of Omak, in the county of Okanogan and 5 State of Washington, have invented certain new and useful Improvements in Box-Press Stamps, of which the following is a specification.

This invention relates to stamping devices for use in connection with fruit box presses.

An important object of this invention is to provide a stamping mechanism for fruit box presses having novel means whereby the 15 desired characters or words may be readily stamped on the box as the cover is pressed on the box and which mechanism does not interfere with the nailing of the cover on the box.

20 A further object is to provide a stamping mechanism for fruit box presses having novel means whereby the printing drum may be readily adjusted for printing the desired matter on the box.

25 Further the invention aims to provide a printing mechanism for fruit box stamps which is entirely automatic in its operation and which is of durable and economical construction.

30 Other objects and advantages of the invention will be apparent during the course of the following description.

In the accompanying drawings, forming a part of this application and in which like 35 numerals are employed to designate like parts throughout the same,

Figure 1 is an elevation of the improved stamping mechanism applied to a fruit box press.

40 Figure 2 is a detailed horizontal sectional view taken on the line 2—2 of Figure 1.

Figure 3 is a perspective of the improved stamping mechanism detached.

45 Figure 4 is a detail sectional view through the printing means of the stamping mechanism.

In the drawing wherein for the purpose of illustration is shown a preferred embodiment of the invention, the numerals 10 design-

50 ate the legs of the press joined by transversely extending struts or beams 11. The legs 10 support a platform 12 upon which a fruit receiving crate 13 is adapted to be

mounted so that the cover 14 may be pressed downwardly into position by means of a 55 pair of pressing or clamping members 15 secured to a transversely extending head 16.

The transversely extending head 16 has connection with vertically arranged links 18, arranged at opposite sides of the frame 60 and having their lower ends connected to the lower links 19 of a pair of toggle levers. Connection between the lower links 19 and the links 18 is by means of brackets 20 having hooks 21 to which coiled springs 22 are 65 connected.

The upper ends of the coiled springs 22 of which there are two are anchored to the frame by hooks 23 and the said coiled springs 22 urge the lower ends of the links 70 19 to the position illustrated in Figure 1.

With reference to Figure 1 it will be observed that the upper portions of the lower links 19 are pivotally connected as indicated at 25 to the lower portions of upper links 75 26 which are in turn pivoted to the frame of the machine as indicated at 27. When the adjacent portions of the links 19 and 26 are drawn inwardly toward the machine the vertically arranged links 18 are drawn 80 downwardly so as to cause the pressing members to force the lid 14 down onto the fruit whereupon the operator may nail the lid in position.

The means employed for moving the adjacent portions of the links 19 and 26 inwardly include rods 28 threaded into the U-shaped members 29 which are pivoted to the pivot elements 25 on opposite sides of the links 19 and 26. The inner portions of 85 the rods 28 are formed with loops 30 to which sprocket chains 31 are connected. The inner ends of the chains 31 have connection with hooks 34 secured on a sprocket wheel generally designated by the numeral 35. 90 The sprocket wheel 35 consists of a pair of offset segments about which the sprocket chains 31 are trained so that when the shaft 38 to which the sprocket wheel is connected 95 is rotated the sprocket wheel will be rotated 100 for drawing the sprocket chains 31 inwardly.

The shaft 38 has a grooved pulley 40 mounted thereon and a cable 41 which is trained about the pulley is anchored at one 105 end of the same as indicated at 42. The

other end of the cable 41 is secured as indicated at 44 to the intermediate portion of a foot lever 45 which is pivoted at its forward end to the frame as indicated at 46. 5 The other end of the foot lever 45 is formed with a foot pedal 48 which when depressed by the foot will draw the cable 41 downwardly and thereby rotate the shaft 38. A latch 49 is pivoted to the foot lever 45 and 10 is adapted to engage on a vertically arranged rack 50 secured to the same. When the foot lever 45 is moved downwardly the same is held in an adjusted position by means of the latch 49 which engages the 15 teeth on the rack 50. When it is desired to release the lever 45 it is merely necessary to exert a downward pressure on the latch 49 whereupon the same will be released from engagement with the rack 50. 20 The improved stamping mechanism includes a pair of spaced parallel sides 52 pivoted at their forward ends to the frame of the machine. The side bars 52 which are arranged in spaced relation are connected 25 intermediate their ends by a U-shaped bracket 53. The upper portions of the sides 52 are in turn connected by a U-shaped head 54 connected to the inner sides of the arms by means of rivets or other suitable fastening 30 devices. The head 54 carries a printing stamp 55 bearing matter which is to be printed on the end of the box. For example, the stamping member 55 which is of rubber may bear the words "Wine Sap" to indicate 35 the brand of apple within the box. In case oranges are packed in the boxes the stamp 55 may bear a word indicating the brand in the box. When the frame formed by the sides 52 and the head 54 is swung inwardly 40 the stamp 55 which is of elongated formation and is supported by the branch 56 of the head is engaged with the box to provide the same with the required data.

The head 54 is provided with a rotatable 45 shaft 58 having a stamping segment 59 secured thereon by means of a set screw 60. The rubber face of the stamping segment 59 may be provided with such data as "Fancy," "Extra fancy," "C-grade" or other 50 suitable data. The segment 59 may be adjusted so that the same will be properly presented to the end of the box. That is to say the desired word or designation may be positioned in alignment with the rubber stamp 55 so that all the data printed on the box 55 will be in the same line. One end of the segment 59 is provided with a spring finger 62 extended laterally beyond the segment and adapted to be received within locking 60 notches 63 in an intermediate wall 64 of the head.

As illustrated in Figure 4 a gear 66 is rotatably mounted on the shaft 58 and is provided with a bushing 67 extended through 65 one of the sides of the head and into the

hub of a stamping cylinder or drum 69. The cylinder or drum 69 is securely connected to the bushing 67 by means of oppositely arranged set screws 70. By reason of this construction, the rotation of the gear 66 70 which is connected or formed integral with the bushing 67 results in the rotation of the member 69 which is provided on its surface with an annular series of numbers or characters 71 adapted to be positioned in 75 alignment with the data on the segment 62 and in alignment with the data on the stamp 55. In this case the characters 71 on the drum 69 are in the nature of numbers. The gear 66 is in mesh with the teeth formed on the inner side of the longitudinally curved rack 72 having supporting branches 73 pivotally connected to the head 54 as indicated at 74. By this construction, the frame formed by the rack 72 and the branches 73 80 may be rotated to a limited degree for rotating the gear 66 and the drum 69. The frame thus formed is provided with an operating handle 75 having a knob 76 forming a gripping means whereby the frame may 85 be rotated for positioning the pointer 77 of the same at the desired point on an arcuate dial 78. By positioning the pointer 77 at the desired point on the dial 78 the cylindrical drum 69 may be adjusted so that the 90 desired character on the periphery of the same may be lined up with the stamp 55. It will be noted that the handle 75 is offset so that the knob 76 of the same will not obstruct the view of the pointer 77 and so 95 that the drum may be readily rotated.

The segment 59 may be rotated to a limited degree by rotating a crank 79 secured to the end of the shaft 58, said crank having connection with a link 80 which is 100 in turn connected to a short link 81 securely connected to the knob 76. By moving the link 80 longitudinally the crank 79 may be rotated for imparting a similar movement to the shaft 58 whereby the segment 59 will 105 be rotated.

The stamping devices are inked by means of a pad 88 supported for swinging movement by a pair of longitudinally curved arms 89 pivoted intermediate their ends as 110 indicated at 90, to the outer ends of outwardly inclined brackets 91. When the frame formed by the arm 52 and associated elements is swung outwardly, a transversely extending bar 92 of the head 54 engages the arms 89 and thereby swings the inking pad 88 into contact with the stamping members 55, 59 and 71 so as to provide them with a fresh supply of ink after each stamping operation. As the printing members move 115 inwardly in the direction of the box the inking pad 88 is swung downwardly to its inoperative position as illustrated in Figure 3.

The stamping mechanism is swung in- 120

wardly by means of a longitudinally curved arm 95 having its forward portion formed with a slot 96 which receives a pivot bolt 97 carried by a crank 98 rigidly secured on the shaft 38. When the shaft 38 is rotated in a clockwise direction by the means previously described the arm or rod 95 is drawn inwardly so as to draw the stamping mechanism into contact with the box.

10 As illustrated in Figure 3 one end portion of the actuating rod 95 is in the form of a pin or shaft 100 slidable through a central opening in the U-shaped connecting member 53. The coiled springs 101 are 15 mounted on the shaft 100 on opposite sides of the U-shaped connecting member 53 and serves to cushion the action of the stamper when the same is moved into contact with the fruit box. In other words the coiled springs 20 101 provide a yieldable connection with the rod 95 and the stamping frame. One of the coiled springs 101 is confined between the connecting member 53 and the shoulder formed at the juncture of the shaft 100 and 25 the rod 95 and the other coiled spring is confined between the connecting member 53 and a nut 102 threaded onto the shaft.

30 A Y-shaped catch generally designated by the numeral 105 is provided with a pair of spaced branches 106 slidable through the connecting portion 53 on opposite sides of the shaft 100 and provided with coiled springs 107 which serve to cushion the action of the stamper. The catch or tripping device 35 105 is also provided with a longitudinally curved shoe 108 which is adapted to contact with the side of the frame so that the shoe is elevated. When the shoe is elevated the notch formed by the juncture of 40 the branches 106 with the shoe 128 is elevated and a longitudinally curved guard 110 is released from locking engagement with the tripping device. The forward portion of 45 the longitudinally curved guard is formed with a right angle bend providing a shoulder 111 adapted to be received within the afore- 50 said notch whereby to provide a locking connection between the actuating rod 95 and the tripping device. When the tripping device 55 shoe 108 is elevated by contact with the frame of the machine, the coiled spring 101 between the shoulder 111 and the connecting portion 53 returns the stamping mechanism to a neutral position. With the 60 stamping mechanism thus moved outwardly to a neutral position the operator may quickly nail the lid on the box. Also with the stamping mechanism thus thrown into a neutral position, the members 59 and 69 65 may be adjusted for stamping the grade and other data on the box.

Having thus described the invention, what is claimed is:—

1. A stamper for fruit presses comprising 65 a frame, an actuating rod slidable through

said frame, coil springs mounted on said rod and contacting with opposite sides of said frame whereby to provide a yieldable connection between the rod and frame, a stamping mechanism carried by said frame, 70 and a tripping device engaged with said rod and having a contact shoe adapted to engage the fruit press.

2. A stamper for fruit presses comprising 75 a frame, an actuating rod slidable through said frame, coil springs mounted on said rod and contacting with opposite sides of said frame whereby to provide a yieldable connection between the rod and frame, a stamping mechanism carried by 80 said frame, a tripping device engaged with said rod and having a contact shoe adapted to engage the fruit press, said tripping device being extended through the frame, and a coil spring confined between the frame 85 and the end of the tripping device.

3. The combination with a fruit box press, having an actuating rod of a frame pivoted to the press and having a cross piece, the outer portion of said actuating rod being 90 slidable through said cross piece, a coiled spring mounted on said actuating rod and engaging said cross piece, and a Y-shaped tripping device having branches slidable through said cross piece and having a shoe 95 adapted to engage said press, said actuating rod being provided with a shoulder engaged by said tripping device.

4. The combination with a fruit box press, 100 of an actuating rod, a frame pivoted to the press and having a cross piece, the outer portion of said actuating rod being slidable through said cross piece, a coiled spring mounted on said actuating rod and engaging said cross piece, a Y-shaped tripping device having branches slidable through said cross piece and having a shoe adapted to engage 105 said press, said actuating rod being provided with a shoulder engaged by said tripping device and springs confined between the 110 ends of said branches and said cross piece.

5. The combination with a fruit box press having an actuating rod, of a frame pivoted to the press and having a cross piece, the outer portion of said actuating rod being 115 slidable through said cross piece, a coiled spring mounted on said actuating rod and engaging said cross piece, a tripping device having branches slidable through said cross piece and having a shoe adapted to engage 120 said press, said actuating rod being provided with a shoulder engaged by said tripping device, springs confined between the ends of said branches and said cross piece, and a longitudinally curved guard 125 extending from said shoulder and overhanging the said first named spring.

6. The combination with a fruit box press having an actuating rod, of a frame pivoted to the press and having a cross piece, the 130

- 4
- outer portion of said actuating rod being 5
slidable through said cross piece, a coiled
spring mounted on said actuating rod and
engaging said cross piece, a Y-shaped tripping
device having branches slidable through
said cross piece and having a shoe
adapted to engage said press, said actuating
rod being provided with a shoulder
engaged by said tripping device, springs
10 confined between the ends of said branches
and said cross piece, a longitudinally curved
guard extending from said shoulder and
overhanging the said first named spring,
and a stamping device carried by said
15 frame.
7. The combination with a fruit box press
having an actuating rod, of a frame pivoted
to the press and having a cross piece, the
outer portion of said actuating rod being
20 slidable through said cross piece, a coiled
spring mounted on said actuating rod and
engaging said cross piece, a Y-shaped tripping
device having branches slidable through
said cross piece and having a shoe
25 adapted to engage said press, said actuating
rod being provided with a shoulder engaged
by said tripping device, springs confined be-
tween the ends of said branches and said
cross piece, a longitudinally curved guard
30 extending from said shoulder and overhang-
ing the said first named spring, a stamping
device carried by said frame, and inking
means for said stamping device.
8. A stamping mechanism for fruit presses,
35 comprising a frame having means whereby
the same may be pivoted to a fruit box
press, an actuating rod slidable through said
frame and having a longitudinally curved
guard provided with a shoulder, a coiled
40 spring confined between said shoulder and
said frame, a tripping device having a notch
receiving said shoulder and provided with a
longitudinally curved shoe adapted to en-
gage the press, said tripping device being
45 adapted to ride on said guard upon the
engagement of said shoe with said press,
and a stamping mechanism carried by said
frame.
9. A stamping mechanism for fruit presses
50 comprising a frame, a shaft carried thereby,
a printing member rigidly secured on said
shaft, a second printing member rotatable
on said shaft, a gear rigidly connected to
said printing member, a rack in mesh with
55 said gear, a knob connected to said rack
for adjusting the same and said rotatable
printing member, and means connecting said
shaft to said knob, whereby the knob forms
a means for adjusting said first named print-
60 ing member.
10. A stamping mechanism comprising a
frame, a shaft carried thereby, a printing
member rigidly secured on said shaft, a sec-
ond printing member rotatable on said shaft,
65 a gear rigidly connected to said rotatable
- printing member, a rack in mesh with said
gear, a knob connected to said rack for adjust-
ing the same and said rotatable printing mem-
ber, a crank connected to said shaft a link
establishing connection between said crank 70
and said knob whereby the knob forms a
means for adjusting said first named print-
ing member.
11. A printing mechanism for fruit presses
comprising a shaft, a printing drum having
a hub surrounding the shaft, a gear having a
bushing rotatable on said shaft and having
75 secure connection with said drum, a rack
having engagement with said gear, a pointer
having connection with said rack, a dial co-
operating with said pointer, and a second
printing member rigidly secured to said
80 shaft and rotatable therewith.
12. A printing mechanism for fruit presses
comprising a shaft, a printing drum having
a hub surrounding the shaft, a gear having
a bushing rotatable on said shaft and having
85 secure connection with said drum, a rack
having engagement with said gear, a pointer
having connection with said rack, and a
second printing member rigidly secured to
said shaft.
13. A printing mechanism for fruit presses
comprising a shaft, a printing drum having
a hub surrounding the shaft, a gear having
95 a bushing rotatable on said shaft and having
secure connection with said drum, a rack
having engagement with said gear, a pointer
having connection with said rack, a dial co-
operating with said pointer, and a second
100 printing member rigidly secured on said
shaft and rotatable therewith.
14. A printing mechanism for fruit presses
comprising a shaft, a printing drum having
a hub surrounding the shaft, a gear having
105 a bushing rotatable on said shaft and having
secure connection with said drum, a rack
having engagement with said gear, a pointer
having connection with said rack, a dial co-
operating with said pointer, a knob having
110 connection with said rack whereby the
pointer may be moved across said dial, a
second printing member rigidly secured to
said shaft, and means connecting said shaft
and said knob.
- 115 15. A printing mechanism for fruit presses
comprising a shaft, a printing drum having
a hub surrounding the shaft, a gear having
a bushing rotatable on said shaft and having
secure connection with said drum, a rack
120 having engagement with said gear, a pointer
having connection with said rack, a dial co-
operating with said pointer, inking means for
said drum, a second printing member se-
cured on said shaft, and a single adjusting
125 member for said first and second named
printing members.
16. A printing mechanism for fruit presses
comprising a frame, a shaft carried thereby,
a gear having a bushing rotatable on said
130

shaft, a printing drum securely connected to said bushing, a printing segment secured on said shaft, a rack engaged with said gear and having branches provided with a pointer, 5 a dial cooperating with said pointer to indicate the position of said segment, means whereby said pointer may be moved across

said dial, a crank connected to said shaft, a link connected to said crank, and forming a means whereby said shaft may be rotated, 10 and inking means for said segment and said drum.

JOSEPH IRWIN POGUE.
